PORTABLE FIREARM FOR FIRING BOMBS

Luigi Savani, Milan, Italy, assignor to Societa Italiana Ernesto Breda per Costruzioni Mecaniche, Milan, Italy

Original application July 13, 1934, Serial No. 735,033. Divided and this application August 17, 1936, Serial No. 96,528. In Italy July 14, 1933

7 Claims. (Cl. 42—1)

This application is a division of my copending application, Serial No. 735,033, filed July 13, 1934.

The present invention relates in general to portable firearms and more particularly has reference to a grenade and bomb-projecting attachment for rifles.

An object of this invention is to provide a grenade and bomb-projecting attachment for rifles, comprising a grenade and bomb-projecting barrel and adjustable means for conducting variable quantities of explosion gases from the barrel of the rifle into said grenade and bomb-projecting barrel to vary the range of projection.

Another object of this invention is to provide a bomb-projecting attachment for rifles, including means in the bomb barrel for imparting a rotary movement to the bomb upon projection.

Still another object of this invention is to provide a bomb-projecting attachment for rifles having an externally rifled sleeve mounted coaxially on the bomb-projecting barrel and adapted to cooperate with an internally rifled extension on the bomb to impart a rotary motion to the bomb when projected.

In order that the invention may be more clearly understood, reference will now be made to the accompanying drawing which shows, by way of example, a preferred embodiment.

In the drawing:

Figure 1 is a fragmentary elevational view, illustrating the bomb-projecting attachment applied to a rifle.

Fig. 2 is a longitudinal sectional view of the structure of Fig. 1.

Fig. 3 is an elevational view of the bomb-projecting attachment.

Fig. 4 is an end or bottom view of the bomb-projecting attachment.

Fig. 5 is a side view, partly in section of a bomb.

In the drawing, in which similar reference characters designate the same or similar parts, the rifle 1 is shown with the bomb-projecting attachment fitted on the rifle barrel 2. As more clearly shown in Fig. 2, the bomb-projecting attachment embodies an externally screw-threaded machine 3 having a socket adapted to receive the muzzle of the rifle barrel and having an axial bore 4 coaxial with the bore of the rifle barrel.

Member 3 is also provided with an offset tubular extension 5, in which is mounted an attaching arm 6. The lower end of arm 6 is equipped with a socket 7 and locking bolt 8 adapted to cooperate with the bayonet-attaching lug 9 of the rifle to securely mount the member 3 on the muzzle of

the rifle barrel.

Again referring to Fig. 2, it will be observed that an internally and externally threaded sleeve 10 is mounted coaxially on the screw-threaded portion of member 3. The upper portion of sleeve 10 has its internal diameter reduced to approximately the size of bore 4 and is provided with a plurality of passages 11 for the lateral escape of explosion gases. The upper portion of sleeve 10 carries a tube 12, the external surface of which is rifled as indicated by reference character 13. Passages 14 are provided between the tube 12 and the member 10 through which the gases escaping from passages 11 may be conducted into the tube 12. An annular valve body 15 is arranged about the sleeve 10 for controlling the flow of gases through the circular passage formed between the lower edge 17 of tube 12 and the annular edge 18 of barrel 16.

The bomb-projecting barrel 16 is threaded on the external threaded portion of sleeve 10 and is adapted to be axially adjusted relatively to sleeve 10 by means of the screw-threaded mounting. This construction provides a bomb-projecting barrel 16 with the central tube 12 positioned coaxially therein.

At this point it should be observed that the lower edge of tube 12 projects downwardly below the upper portion of sleeve 10 to form a seat 17 for valve 15 which is moved up to its seat by means of the annular rib 18, formed at the upper screw-threaded portion of barrel 16.

In practice, a bomb 20 is placed in barrel 16 and is formed with a skirt-like extension which surrounds tube 12. Rifling or other means are formed on the interior of the extension of the bomb which cooperate with the rifling on the tube 12 to cause the bomb to rotate when projected.

By directing the gases escaping from passages 11 through passages 14 into the interior of tube 12, the propulsive force imparted to the bomb may be increased. For this purpose the barrel 16 is rotated to shift the valve body 15 to vary the quantity of gases escaping between the tube 12 and barrel 16 to enable the marksman to determine the position of valve body 15 and the range of the projector, indicia are arranged on the exterior of the barrel as is clearly shown in Figs. 1 and 3. When the barrel 16 is in its uppermost position, the valve body 15 is gripped between seat 17 and rib 18 so that all of the gases discharged from barrel 16 will flow through the central bore of member 10 and the passages 11 and 14 into the interior of tube 12.

A sighting mechanism 19 for use with the

bomb-projecting attachment is also carried by the member 3.

While I have shown and described the preferred embodiment of my invention, I wish it to be understood that I do not confine myself to the precise details herein set forth by way of illustration, as it is apparent that many changes and variations may be made therein by those skilled in the art, without departing from the spirit of the invention or exceeding the scope of the appended claims.

I claim:

1. A bomb-projecting attachment for rifles, comprising a bomb-projecting barrel, an externally rifled tube coaxially positioned in said barrel and adapted to cooperate with an internally rifled extension of a bomb to impart a rotary motion to the bomb upon projection, means for detachably mounting said tube and bomb-projecting barrel coaxially on the muzzle of a rifle, said mounting means having a bore in axial alignment with the bore of the rifle for conveying explosion gases from the rifle to said tube, said mounting means also having passages for the escape of gases from the bore thereof into said bomb-projecting barrel, and means actuated by an axial displacement of said bomb-projecting barrel on said mounting means for controlling the flow of gases through said passages.

2. A bomb-projecting attachment for rifles, comprising a tubular member for attachment to the muzzle of a rifle barrel and provided with a bore in alignment with the bore of the rifle barrel, a sleeve mounted on said member and having a bore registering with the bore in said member, a tube carried by and surrounding the outer portion of said sleeve, a bomb-projecting barrel mounted on said sleeve and surrounding said tube in spaced relation thereto adapted to receive a bomb having a tubular projection which surrounds said tube for receiving the explosion gases discharged from the muzzle of the rifle through the bore of said member into said tube, said sleeve having passages for the escape of gases from its bore into the bomb-projecting barrel, and means for directing gases, escaping from said passages, into said tube.

3. A bomb-projecting attachment for rifles, comprising a tubular member for attachment to the muzzle of a rifle barrel and provided with a bore in alignment with the bore of the rifle barrel, a sleeve mounted on said member and having a bore registering with the bore in said member, a tube carried by and surrounding the outer portion of said sleeve, a bomb-projecting barrel mounted on said sleeve and surrounding said tube in spaced relation thereto adapted to receive a bomb having a tubular projection which surrounds said tube for receiving the explosion gases discharged from the muzzle of the rifle through the bore of said member into said tube, said sleeve having passages for the escape of gases from its bore into the bomb-projecting barrel, an annular valve body surrounding said sleeve adjacent said passages, and means carried by said bomb-projecting barrel for forcing said valve body into engagement with the lower portion of said tube to prevent the flow of gases into said bomb-projecting barrel and to deflect the same into said tube.

4. A bomb-projecting attachment for rifles, comprising a tubular member for attachment to the muzzle of a rifle barrel and provided with a bore in alignment with the bore of the rifle barrel, a sleeve mounted on said member and having

a bore registering with the bore in said member, a tube carried by and surrounding the outer portion of said sleeve, a bomb-projecting barrel mounted on said sleeve and surrounding said tube in spaced relation thereto adapted to receive a bomb having a tubular projection which surrounds said tube for receiving the explosion gases discharged from the muzzle of the rifle through the bore of said member into said tube, said sleeve having passages for the escape of gases from its bore into the bomb-projecting barrel, means for directing gases, escaping from said passages, into said tube, and rifling on the exterior of said tube adapted to cooperate with internal rifling on a tubular extension of a bomb for imparting rotary motion thereto, upon projection.

5. A bomb-projecting attachment for rifles, comprising a tubular member for attachment to the muzzle of a rifle barrel and provided with a bore in alignment with the bore of the rifle barrel, a sleeve mounted on said member and having a bore registering with the bore in said member, a tube carried by and surrounding the outer portion of said sleeve, a bomb-projecting barrel mounted on said sleeve and surrounding said tube in spaced relation thereto adapted to receive a bomb having a tubular projection which surrounds said tube for receiving the explosion gases discharged from the muzzle of the rifle through the bore of said member into said tube, said sleeve having passages for the escape of gases from its bore into the bomb-projecting barrel, an annular valve body surrounding said sleeve adjacent said passages, means carried by said bomb-projecting barrel for forcing said valve body into engagement with the lower portion of said tube to prevent the flow of gases into said bomb-projecting barrel and to deflect the same into said tube, and rifling on the exterior of said tube adapted to cooperate with internal rifling on a tubular extension of a bomb for imparting rotary motion thereto upon projection.

6. A bomb-projecting attachment for rifles, comprising a tubular member for attachment to the muzzle of a rifle barrel and provided with a bore in alignment with the bore of the rifle barrel, a sleeve mounted on said member and having a bore registering with the bore in said member, a tube carried by and surrounding the upper outer portion of said sleeve, the lower portion of said sleeve being externally threaded, a bomb-projecting barrel having a lower internally threaded portion threadedly mounted on the threaded portion of said sleeve and an upper portion surrounding the upper portion of said tube in spaced relation thereto adapted to receive a bomb having a tubular projection which surrounds said tube for receiving the explosion gases discharged from the muzzle of the rifle through the bore of said member into said tube, said sleeve having passages for the escape of gases from its bore into the bomb-projecting barrel, an annular valve body surrounding said sleeve adjacent said passages, means carried by said bomb-projecting barrel for forcing said valve body into engagement with the lower portion of said tube to prevent the flow of gases into said bomb-projecting barrel and to deflect the same into said tube upon rotation of said bomb-projecting barrel to axially displace it in the direction of projection of the bomb.

7. A bomb-projecting attachment for rifles, comprising a tubular member for attachment to the muzzle of a rifle barrel and provided with a

bore in alignment with the bore of the rifle barrel, a sleeve mounted on said member and having a bore registering with the bore in said member, a tube carried by and surrounding the upper 5 outer portion of said sleeve, the lower portion of said sleeve being externally threaded, a bomb-projecting barrel having a lower internally threaded portion threadedly mounted on the threaded portion of said sleeve and an upper portion surrounding the upper portion of said tube 10 in spaced relation thereto adapted to receive a bomb having a tubular projection which surrounds said tube for receiving the explosion gases discharged from the muzzle of the rifle 15 through the bore of said member into said tube, said sleeve having passages for the escape of

gases from its bore into the bomb-projecting barrel, an annular valve body surrounding said sleeve adjacent said passages, means carried by said bomb-projecting barrel for forcing said valve body into engagement with the lower portion of said tube to prevent the flow of gases into said bomb-projecting barrel and to deflect the same into said tube upon rotation of said bomb-projecting barrel to axially displace it in the direction of projection of the bomb, indicia on the exterior of said bomb-projecting barrel, and a pointer carried by said member adapted to cooperate with said indicia to directly indicate the degree of closure of said valve body. 10 15
